HEAT SENSITIVE DEVICE

Siegfried G. Isserstedt, Minneapolis, Minn., assignor to Minneapolis-Honeywell Regulator Company, Minneapolis, Minn., a corporation of Delaware

Application January 17, 1942, Serial No. 427,207

13 Claims. (Cl. 200—140)

This invention is directed broadly to a device which will respond to radiant heat, and is more particularly concerned with a device of this type which may be accurately calibrated to indicate when the intensity of heat radiation reaches a predetermined value.

The invention relates to a heat responsive device in the form of a sealed chamber containing a heat expansible fluid of some type, such as air, and which has a wall through which radiant heat may freely pass. A heat absorbing means is located in the chamber in order to absorb radiant heat passing into the chamber for the purpose of heating the air therein. Although the heat absorbing means used in the chamber may be made of relatively light material having a low heat carrying capacity, such as a thin sheet of metal foil, the walls of the chamber must necessarily be of substantial mass in order to give the construction strength, and these walls will absorb a substantial amount of heat and therefore have a material effect in additionally heating the air in the chamber. Therefore when the amount of radiant heat passing into the chamber has been materially reduced or entirely cut off, the residual heat in the walls of the device will continue to heat the air and thereby prevent it from contracting and reducing the pressure within the chamber an amount corresponding to the actual amount of radiant heat which the chamber is receiving.

It is therefore one of the main objects of this invention to compensate a device of the above type for the effect which the walls of the device have upon the temperature of the air within the chamber.

A further object of the invention is to accomplish this compensating effect by means of a second chamber having an expansible fluid therein and in which the walls thereof are equally affected by radiant heat so that the walls of the first chamber and the walls of the second chamber will affect their fluid equally. The invention further includes the feature of providing a means responsive to difference in pressure of the fluids in the two chambers so that the effect of the wall temperature of the second chamber will act on the differential pressure responsive means to compensate it for the effect of the wall on the temperature of the fluid in the first chamber.

A still further object of the invention is to insert a heat absorbing means in the second, or compensating, chamber in order to assist the compensation of the wall temperature effect on

the first chamber. The invention also includes the feature of providing a means for adjusting the effect which the radiant heat has on the absorbing means in the compensating chamber in order that this device may be properly calibrated. The last named means may be in the form of an adjustable heat shield for shielding variable portions of the heat absorbing means in the compensating chamber.

10 Another object of the invention is to make the first member of a form having a substantially circular cross-section and then have the compensating chamber in the form of an annulus surrounding the first chamber.

15 Still another object of the invention is to place the second chamber immediately in front of the first chamber so that the face of the first chamber forms the rear wall of the second or compensating chamber and the radiant heat passes serially through said chambers, passing first through the compensating chamber and then through the first chamber. In such case a diaphragm is located at the rear of the first chamber for responding to the pressure therein, and a 20 passageway communicates or connects the opposite side of the diaphragm and the second chamber so that the diaphragm will respond to the difference in pressure between the two chambers.

25 30 These and other objects will readily become apparent to those who are skilled in the art as the following specification is read in the light of the accompanying drawing in which,

Figure 1 is a front elevation of a first modification of my invention,

Figure 2 is a section taken along the line 2—2 of Figure 1, and

Figure 3 is a longitudinal sectional view of a modified form of my invention.

40 Referring now to Figures 1 and 2 of the drawing, the reference numeral 10 indicates a housing having a pair of concentric circular walls 11 and 12 forming a first open-ended cylindrical chamber 13 and a second annular open-ended 45 chamber 14 which surrounds the chamber 13. A circular face plate 15 closes the open end of the two chambers 13 and 14. The face plate 15 must be made of some material which will transmit radiant heat so that it can pass into the chambers 13 and 14. This face plate is preferably made of Lucite. Any other material which will transmit radiant heat such as glass or other plastics may be used if desired. For the purpose of convenience the housing 10 is also made of 50 Lucite, and the housing 10 and face plate 15 are 55

fused together in order to make the two chambers 13 and 14 air tight.

The two chambers 13 and 14 must be filled with a heat expansible fluid of some kind. In this particular case hydrogen is used, although many other fluids, such as air, may be used if desired. Located within the chamber 13 is a heat absorbing means in the form of a thin metal foil, such as aluminum foil, the side facing the face plate 15 being blackened in order that it may more readily absorb the radiant heat passing through the face plate 15. The metal foil 17 is connected to the wall 11 at three different points indicated at 18 so that when the hydrogen within the chamber 13 is heated by the metal foil as it absorbs the radiant heat passing into the chamber 13, the hydrogen may readily circulate around it so that all of the hydrogen in this chamber will rapidly come to the same temperature.

A U tube 20 is connected at one end to the interior of the chamber 13 and at the other end to the chamber 14. The U portion of the tube carries a quantity of liquid such as colored water or mercury so that the liquid will rise or fall in the two legs of the tube, depending upon the difference in pressure existing between the two chambers 13 and 14.

The operation of the device as described thus far should now be apparent. Assuming that there is no radiant heat striking the face plate 15, the temperature of the hydrogen in the two chambers 13 and 14 should be the same, and therefore the liquid 21 should be at the same level in the two legs of the U tube 20. If radiant heat should now strike the face plate 15, it will pass therethrough and into the chambers 13 and 14 where it will rapidly be absorbed by the metal foil 17 which will immediately heat the hydrogen in the chamber 13. This will cause an increase in pressure in the chamber 13 and the liquid will be forced downwardly in the leg 22 of the U tube and upwardly in the leg 23. The radiant heat will not only be absorbed by the metal foil 17 but also to a certain extent by the face plate 15 and also by the wall 11. As 11 and 15 increase in temperature they will also have a certain heating effect upon the hydrogen in the chamber 13. This is an undesirable effect because the temperatures of the members 11 and 15 lag considerably behind the changes in the intensity of the radiant heat. The metal foil 17 has only a very slight mass and therefore its temperature will very closely follow the amount of radiant heat passing through the face plate 15. It is therefore desired that the indicating liquid 21 should move in the U tube in direct accordance with the amount of heat absorbed by the metal foil 17 and communicated to the hydrogen in the chamber 13 and therefore the effect which the wall 11 and face plate 15 have on the temperature of the hydrogen in the chamber 13 should be removed if the liquid 21 is to accurately indicate the intensity of the heat radiation striking the face plate 15.

In order to compensate for the effect of the wall 11 and face plate 15 upon the temperature of the hydrogen in the chamber 13, an equal and opposite effect is produced in the chamber 14. Thus the radiant heat will also heat that portion of the face plate 15 which closes the chamber 14 as well as the wall 11 and the wall 12 and their temperature will affect the temperature of the hydrogen in the chamber 14. This effect will lag behind the actual changes in in-

tensity of heat radiation in the same manner as will the effect of the face plate 15 and wall 11 upon the temperature of the hydrogen in the chamber 13. Therefore, if these effects are equal and opposite then the indicating liquid 21 will move in direct accordance with the intensity of the heat radiation passing into the chamber 13 and absorbed by the metal foil 17.

One of the desirable features of the modification shown in Figures 1 and 2 is that the device can be calibrated after it has once been set up. This is accomplished by so designing the two chambers 13 and 14 that the effect of the heat upon the walls 11 and 12 is not quite sufficient to properly compensate the device. The additional compensation is obtained by the provision of a heat absorbing ring 25 mounted in the chamber 14. This ring is made of some suitable material which has a substantial mass whose temperature will therefore lag behind the variations in heat radiations in the same manner as the walls 11 and 12 and the face plate 15. In order to calibrate the device, means have been provided for varying the total area of the ring 25 which the heat radiations may strike. This means is in the form of an arcuate heat shield 26 which is mounted upon a bellows 27 and adjusted vertically by means of a manually operable screw 28. As the heat shield 26 is lowered, more and more of the ring 25 is subjected to the heat radiations passing through the plate 15, and as this heat shield is raised, it cuts off more and more of the heat radiations. This heat shield must necessarily be made of some heat insulating material which will not have any substantial effect upon the temperature of the air in the chamber 14 other than the effect in shielding variable portions of the ring 25. In this manner the compensating effect of the chamber 14 may be varied sufficiently to properly calibrate the device as a whole after it has once been installed.

Referring now to Figure 3, a modified form of my invention is shown. This modification includes a base member 30 and a face plate 31 which are circumferentially shouldered and which fit together to form a unitary structure. These members are internally hollowed out to form a chamber which is substantially ellipsoidal in shape. These two members clamp between them a plurality of tabs or ears on a substantially circular sheet of metal foil 32, the circumference of this sheet of metal foil being slightly less than the major axis of the ellipsoid so that the hydrogen which is sealed in the chamber may circulate freely. The cup shaped member 34 having a face 35 is inserted over the two members 30 and 31, the face being spaced from the face plate 31 and forming a chamber between the face 35 and the face plate 31. This chamber 36 is also filled with hydrogen.

The base member 30 is provided with a diaphragm chamber in which a movable diaphragm 37 is circumferentially clamped against the base member 30 by means of a plug 38. The chamber 38 communicates with one side of the diaphragm 37 through the passage 39. The other side of the diaphragm 37 carries a stem 40 which extends through an opening in the plug member 38. A closure member 42 seats on the base member 30 and cooperates with the cup shaped member 34 to seal the interior of the entire device from the external atmosphere. A cut-away portion 43 in the cup 34 connects the chamber 36 with that side of the diaphragm 37 which carries the stem 40. Thus, the diaphragm 37 responds to the

difference in the pressure between the chamber 33 and the chamber 36.

The closure member 42 carries a pair of stationary contacts 45 and 46 between which a flexible contact blade 47 is adapted to oscillate. One end of this flexible blade is supported by and electrically connected to a contact member 49. The stem 40 is adapted to be oscillated by the diaphragm 37 upon variations in pressure in the chambers 33 and 36 and this stem is connected to the flexible blade 47 and is adapted to cause it to alternately engage the stationary contacts 46 or 45, depending upon the relative pressures in the two chambers.

In this modification, the radiant heat must pass successively through the chamber 36 and chamber 33. For this reason the face plate 31 and the face 35 of the cup 34 must be made of some material which will transmit the heat radiation. Preferably, the entire construction, that is the cup 34, face plate 31, base 30 and closure member 42 are all made of Lucite so that they may be readily sealed together to form an air tight enclosure. It will be appreciated however that other plastics may be used to advantage if desired.

The operation of this device is substantially the same as the device shown in Figures 1 and 2. When no heat radiation is striking the face 35, the hydrogen in the chambers 36 and 33 is at one temperature, the pressures across the diaphragm 37 are equal, and this diaphragm is therefore in a position in which the contact blade 47 is in engagement with the stationary contact 45. As heat radiations strike the face 35 and pass into the chamber 33, they will be absorbed by the blackened surface of the metal foil 32 which will thus cause heating of the hydrogen in the chamber 33. This will cause an increase in the pressure therein, and when the intensity of the heat radiation striking the face 35 has increased sufficiently, this pressure will cause the diaphragm 37 to expand sufficiently to separate the contact blade 47 from the stationary contact 45. As in the case of the modification shown in Figures 1 and 2, the walls of the chamber 33 formed by the face plate 31 and the base 30 will also be heated to a certain extent by the heat radiations. The temperature of these walls will obviously affect the temperature of the hydrogen in the chamber 33 and as this effect lags considerably behind the changes in intensity of the heat radiations it is an undesirable effect and therefore should be compensated. This compensation is attained in this modification by means of the cup 34 and chamber 36. The cup 34 is so designed that it will absorb sufficient heat to increase the pressure of the hydrogen in the chamber 36 in the same amount that the face plate 31 and base 30 will increase the pressure of the hydrogen in the chamber 33. These two effects are opposing and therefore the chamber 36 will compensate this effect of the chamber 33 so that the pressure in the chamber 33 which affects the diaphragm 37 will be dependent entirely upon the amount of heat absorbed by the metal foil 32.

As the intensity of the radiant heat increases, it will be apparent that the difference in pressure between the chambers 33 and 36 will increase with the result that the diaphragm 37 will eventually move the resilient contact blade 47 over into engagement with the stationary contact 46. It is therefore apparent that as long as the intensity of the heat radiations is within a predeter-

mined range, the resilient contact 47 will be out of engagement with both of the contacts 45 and 46, but that when the intensity of these heat radiations is below a predetermined range the blade 47 will engage contact 45 while if the intensity goes above this range the blade 47 will engage the contact 46. This device will therefore close one circuit when the intensity of the heat radiations is above a predetermined range and close another circuit when the heat radiation intensity is below a certain range.

The main advantage of this device over the device shown in Figures 1 and 2 is that it is a more compact unit and also a smaller unit. This compactness is accomplished by causing the heat radiations to pass successively through the two chambers instead of arranging these chambers so that the heat radiations strike them simultaneously. In order to get the proper compensating effect, it is only necessary to design the cup 34 so that the heating of this cup will have the same effect on the pressure in the chamber 36 as the heating of the face plate 31 and base 30 have on the temperature and pressure of the hydrogen in the chamber 33.

It will be apparent also that the two chambers of both modifications of my invention, when acting in opposition as shown, compensate each other for variations in ambient temperature. Thus variations in ambient temperature will have no effect upon the liquid in the U tube of Figures 1 and 2 or upon the diaphragm 37 of Figure 3.

As many changes and modifications of this invention will doubtless occur to those who are skilled in the art, I wish it to be understood that I intend to be limited by the scope of the appended claims and not by the specific embodiments which have been disclosed herein only for the purposes of illustration.

I claim as my invention:

1. A radiant heat responsive device comprising in combination, housing means having walls forming a pair of sealed pressure chambers, a heat expandable fluid in said chambers, means responsive to the difference in pressure of the fluid in said chambers, said pressure responsive means sealing said chambers with respect to each other, said housing means having a portion capable of transmitting radiant heat therethrough and into said first chamber, means in said first chamber absorbing the radiant heat for heating the fluid therein, the walls of said first chamber absorbing a certain amount of heat thus producing an additional effect on the temperature of the fluid therein, the walls of said second chamber being designed to absorb sufficient heat to raise the temperature of the fluid therein an amount to just balance said additional effect on the fluid in said first chamber, at least one of said walls being common to both chambers for heating the fluid therein, whereby said pressure responsive means responds at all times to the amount of radiant heat striking said housing and is unaffected by the changes in temperature of the walls of said housing.

2. A radiant heat responsive device comprising in combination, housing means having walls forming a pair of sealed pressure chambers, a heat expandable fluid in said chambers, means responsive to the difference in pressure of the fluid in said chambers, said pressure responsive means normally sealing said chambers with respect to each other, said housing means having a portion capable of transmitting radiant heat

therethrough and into said first chamber, means in said first chamber absorbing the radiant heat for heating the fluid therein, the walls of said first chamber absorbing a certain amount of heat thus producing an additional effect on the temperature of the fluid therein, said housing having a portion capable of transmitting radiant heat into said second chamber, means within said second chamber for absorbing radiant heat for heating the fluid therein, the walls of said second chamber and the heat absorbing means in said second chamber being designed to compensate said pressure responsive means for changes in pressure due to said additional effect upon the temperature of the fluid in said first chamber, at least one of said walls being common to both chambers for heating the fluid therein.

3. A radiant heat responsive device comprising in combination, housing means having walls forming a pair of sealed pressure chambers, a heat expandable fluid in said chambers, means responsive to the difference in pressure of the fluid in said chamber, said housing means having a portion capable of transmitting radiant heat therethrough and into said first chamber, means in said first chamber absorbing the radiant heat for heating the fluid therein, the walls of said first chamber absorbing a certain amount of heat thus producing an additional effect on the temperature of the fluid therein, said housing having a portion capable of transmitting radiant heat into said second chamber, means within said second chamber for absorbing radiant heat for heating the fluid therein, the walls of said second chamber and the heat absorbing means in said second chamber being designed to compensate said pressure responsive means for changes in pressure due to said additional effect upon the temperature of the fluid in said first chamber, and means for adjusting the proportional amount of radiant heat absorbed by the absorbing means in said second chamber whereby the compensating effect of said second chamber may be properly adjusted.

4. A radiant heat responsive device comprising in combination, housing means having walls forming a pair of sealed pressure chambers, a heat expandable fluid in said chambers, means responsive to the difference in pressure of the fluid in said chamber, said housing means having a portion capable of transmitting radiant heat therethrough and into said first chamber, means in said first chamber absorbing the radiant heat for heating the fluid therein, the walls of said first chamber absorbing a certain amount of heat thus producing an additional effect on the temperature of the fluid therein, said housing having a portion capable of transmitting radiant heat into said second chamber, means within said second chamber for absorbing radiant heat for heating the fluid therein, the walls of said second chamber and the heat absorbing means in said second chamber being designed to compensate said pressure responsive means for changes in pressure due to said additional effect upon the temperature of the fluid in said first chamber, and means for adjusting the proportional amount of radiant heat absorbed by the absorbing means in said second chamber whereby the compensating effect of said second chamber may be properly adjusted, said last named means comprising a heat shield of low heat capacity for shielding various

amounts of said heat absorbing means from said heat radiations.

5. A radiant heat responsive device comprising a housing having walls forming a sealed chamber, a portion of said housing being capable of transmitting radiant heat therethrough to the interior of said chamber, a heat expandable fluid in said chamber, means absorbing radiant heat passing through said housing for heating said fluid an amount dependent upon the intensity of heat radiations striking said housing, the walls of said housing also absorbing radiant heat for producing an additional heating effect upon said fluid, means responsive to the pressure in said chamber, means automatically producing a pressure on said pressure responsive means which is opposite and substantially equal to the pressure change in said fluid resulting from said additional heating effect, whereby the position assumed by said pressure responsive means will be at all times dependent solely upon the intensity of the heat radiations striking said housing, and means for manually adjusting the effect of said automatic means upon said pressure responsive means.

6. A radiant heat responsive device comprising in combination, housing means having walls forming a pair of sealed pressure chambers, a heat expandable fluid in said chambers, a diaphragm sealing said chambers with respect to each other and movable upon variations in the pressure difference between the fluid in the two chambers, said housing means having a portion capable of transmitting radiant heat therethrough and into said first chamber, means in said first chamber absorbing the radiant heat for heating the fluid therein, the walls of said first chamber absorbing a certain amount of heat thus producing an additional effect on the temperature of the fluid therein, the walls of said second chamber being designed to absorb sufficient heat to raise the temperature of the fluid therein an amount to just balance said additional effect on the fluid in said first chamber, whereby said diaphragm is positioned at all times in accordance with the amount of radiant heat striking said housing and is independent of the temperature of the walls of said housing, and switch means operated by said diaphragm when the intensity of the heat radiations striking said housing reach a predetermined value.

7. A radiant heat responsive device comprising in combination, a cup shaped housing forming a first chamber having a wall portion at one side capable of transmitting radiant heat within said chamber, means forming an annular chamber surrounding said first chamber, said second chamber having a wall portion capable of transmitting radiant heat within said second chamber, the wall portion for said second chamber being on the same side as the wall portion of said first chamber, a heat expandable fluid in said chambers, means responsive to the difference in pressure in said two chambers, and means in said first chamber for absorbing radiant heat passing through its wall portion and expanding the fluid therein, the wall portions of both of said chambers absorbing radiant heat and therefore affecting the temperature and pressure of the fluid in their respective chambers, the pressure in said second chamber tending to balance the pressure in said first chamber.

8. A radiant heat responsive device comprising in combination, a cup shaped housing forming a first chamber having a wall portion at one side

capable of transmitting radiant heat within said chamber, means forming an annular chamber surrounding said first chamber, said second chamber having a wall portion capable of transmitting radiant heat within said second chamber, the wall portion for said second chamber being on the same side as the wall portion of said first chamber, a heat expansible fluid in said chambers, means responsive to the difference in pressure in said two chambers, means in said first chamber for absorbing radiant heat passing through its wall portion and expanding the fluid therein, the wall portions of both of said chambers absorbing radiant heat and therefore affecting the temperature and pressure of the fluid in their respective chambers, and means in said second chamber for absorbing radiant heat and heating the fluid therein, said last named means being so chosen that its effect plus the effect of the walls of said second chamber upon the fluid of said first chamber upon the fluid therein.

9. A radiant heat responsive device comprising in combination, a cup shaped housing forming a first chamber having a wall portion at one side capable of transmitting radiant heat within said chamber, means forming an annular chamber surrounding said first chamber, said second chamber having a wall portion capable of transmitting radiant heat within said second chamber, the wall portion for said second chamber being on the same side as the wall portion of said first chamber, a heat expansible fluid in said chambers, means responsive to the difference in pressure in said two chambers, means in said first chamber for absorbing radiant heat passing through its wall portion and expanding the fluid therein, the wall portions of both of said chambers absorbing radiant heat and therefore affecting the temperature and pressure of the fluid in their respective chambers, means in said second chamber for absorbing radiant heat and heating the fluid therein, said last named means being so chosen that its effect plus the effect of the walls of said second chamber upon the fluid therein compensate for the effect of the walls of said first chamber upon the fluid therein, and means for adjusting the proportion of radiant heat absorbed by the absorbing means in said second chamber whereby the compensating effect of said second chamber upon said first may be properly adjusted.

10. A radiant heat responsive device comprising in combination, a cup shaped housing forming a first chamber having a wall portion at one side capable of transmitting radiant heat within said chamber, means forming an annular chamber surrounding said first chamber, said second chamber having a wall portion capable of transmitting radiant heat within said second chamber, the wall portion for said second chamber being on the same side as the wall portion of said first chamber, a heat expansible fluid in said chambers, means responsive to the difference in pressure in said two chambers, means in said first chamber for absorbing radiant heat passing through its wall portion and expanding the fluid therein, the wall portions of both of said chambers absorbing radiant heat and therefore affecting the temperature and pressure of the fluid in their respective chambers, and means in said second chamber for absorbing radiant heat and heating the fluid therein, said last named means being so chosen that its effect plus the effect of the walls of said

second chamber upon the fluid therein compensate for the effect of the walls of said first chamber upon the fluid therein, a heat shield for shielding a portion of said last mentioned means from the radiant heat passing into said second chamber, and means for adjusting said shield to vary its position and hence the area of the means which it shields.

11. A radiant heat responsive device comprising in combination, housing means having walls forming first and second chambers, said first chamber being located behind of said second chamber, portions of said walls being capable of transmitting radiant heat and being so located that radiant heat may pass through said second chamber and into said first chamber, a heat expansible fluid in both of said chambers, means responsive to the difference between the pressures of the fluid in said chambers, and means in said first chamber for absorbing radiant heat for heating and expanding the fluid therein, said radiant heat also heating the walls of said first and second chambers which heat and expand the fluid in said chambers, the position and mass of said walls being such that they affect the fluid in said two chambers equally.

12. A radiant heat responsive device comprising in combination, wall means comprising a base and a face plate forming a chamber, a second face plate cooperating with said first face plate to form a second chamber, said face plates being capable of transmitting radiant heat whereby radiant heat may pass through said second chamber and into said first chamber, a heat expansible fluid in said chambers, means in said first chamber absorbing radiant heat passing into said first chamber and heating and expanding the fluid therein, and means responsive to the difference between the pressures of the fluid in said chambers, said radiant heat being absorbed to a certain extent by the walls of said chambers and affecting the temperature of the fluid therein, said last named effects being substantially the same whereby said second chamber will compensate the first for such effects.

13. A radiant heat responsive device comprising in combination, wall means comprising a base and a face plate forming a chamber, a second face plate cooperating with said first face plate to form a second chamber, said face plates being capable of transmitting radiant heat whereby radiant heat may pass through said second chamber and into said first chamber, a heat expansible fluid in said chambers, means in said first chamber absorbing radiant heat passing into said first chamber and heating and expanding the fluid therein, means sealing said first chamber including a diaphragm subject at one side to the pressure therein, means affording communication between said second chamber and the opposite side of said diaphragm whereby said diaphragm responds to the difference in pressure in the fluid in said chambers, said diaphragm being so located with respect to said chambers as not to interfere with the passage of radiant heat therethrough, said walls of said two chambers being so designed as to absorb radiant heat in amounts which will expand the fluid in said chambers to produce substantially equal effects upon said diaphragm whereby said diaphragm responds only to the amount of heat absorbed by said absorbing means in said first chamber.

SIEGFRIED G. ISSENSTEDT.
